Filed Nov. 15, 1967, Ser. No. 9,430

Term of patent 14 years

U.S. Cl. D87—1
Int. Cl. D3—99; D9—04

FIG. 1

FIG. 3

FIG. 4

FIG. 5

FIG. 1 is a perspective view of the container for memory discs, showing our new design;

FIG. 2 is a cross sectional view through the container taken along the section line 2—2 of FIG. 1;

FIG. 3 is a top view thereof on a reduced scale;

FIG. 4 is a bottom view thereof on a reduced scale; and

FIG. 5 is a cross sectional view on an enlarged scale of the handle of the container for memory discs taken along the section line 5—5 of FIG. 2.

The lines appearing on the top surface in FIGS. 1 and 3 are intended to represent the ribs on the cover as shown in FIG. 2 and which extend about the entire cover as circles thereon. Similarly, the lines appearing on the bottom surface in FIG. 4 represent the circular ribs on the bottom as shown in FIG. 2.

We claim:

The ornamental design for a container for memory discs, as shown and described.
